United States Patent

Des. 236,857
Patented Sept. 16, 1975

236,857

WALLET

Gordon D. Lookatch, 6200 N. Sunny Point Road,
Glendale, Wis. 53217

Filed July 5, 1973, Ser. No. 376,326

Term of patent 14 years

Int. Cl. D3—01

U.S. Cl. D87—3 A

FIG. 1 is a front, top and left side perspective view of a wallet showing my new design with the second compartment in partially opened condition;

FIG. 2 is a rear elevational view in closed condition;

FIG. 3 is a top plan view thereof;

FIG. 4 is a front elevational view thereof;

FIG. 5 is a bottom plan view thereof;

FIG. 6 is a left side elevational view thereof; and

FIG. 7 is a right side elevational view thereof.

I claim:

The ornamental design for a wallet, as shown and described.
